A. V. Tracy

UNITED STATES PATENT OFFICE.

SEIKICHI NORO, OF MIDLAND PARK, NEW JERSEY.

ATTACHMENT FOR HORSESHOES.

1,307,636.

Specification of Letters Patent. Patented June 24, 1919.

Application filed December 19, 1918. Serial No. 267,431.

To all whom it may concern:

Be it known that I, SEIKICHI NORO, a subject of the Emperor of Japan, residing at Midland Park, in the county of Bergen 5 and State of New Jersey, have invented certain new and useful Improvements in Attachments for Horseshoes, of which the following is a specification.

The object of my invention is to provide 10 a novel anti-slipping attachment for horseshoes, having provision whereby the device may be readily applied to and removed from horseshoes, adjusted to fit horseshoes of different sizes, and whereby the parts thereof 15 may be readily assembled and disassembled as desired.

With the above and related objects in view, 20 my invented attachment consists of the elements and the combinations of them herein- 25 after described and claimed.

In the accompanying drawings, illustrating my invention,

Figure 1 is a side view of my improved attachment applied to a horseshoe,

Fig. 2 is a bottom view thereof,

Fig. 3 is a rear view thereof, and

Fig. 4 is a perspective view of the heel member of the attachment.

Referring to the drawings, 2 designates a 30 horseshoe, and 3 and 4 the heel and toe members, respectively, of the attachment which is applied thereto.

The heel member 3 is adapted to extend beneath the rearward portion of the horseshoe 2, and it comprises two bars or sections which are herein termed first and second sections 5 and 6, respectively. The outer ends of the sections 5 and 6 are provided with upwardly extending projections 7 40 which are adapted to engage the outer face of the horseshoe 2 on the respective sides thereof. The sections 5 and 6 are arranged side by side and they are adapted to slide longitudinally relatively to each other to adjust the projections 7 toward and from each 45 other to fit horseshoes of different sizes.

The sections 5 and 6 have slots 8 and 9, respectively, formed therein; and the section 50 6 is provided with a pin 10 which projects fixedly from the inner end thereof and through the slot 8 in the section 5. The outer end of the pin 10 has a vertically extending bar head 11 which confines the first section 5 between it and the second section 55 6 and permits the sections 5 and 6 to be adjusted longitudinally relatively to each

other. In assembling the sections 5 and 6, one section is turned to an angle relatively to the other to bring the bar head 11 into parallel relation with the slot 8 in the section 5, permitting the head 11 to be passed through the slot 8. Afterward, when the sections are brought into parallel relationship, as shown in the drawings, the head 11 holds the sections together. The sections 5 60 and 6 may be separated or disassembled by a reversal of the operation just described.

The section 5 is provided with a screw-threaded pin 12 which projects fixedly from the inner end thereof and through and beyond the slot 9 in the second section 6; and screwed on to the end of the pin 12 is a nut 13 between which and the first section 5 the second section 6 is clamped to secure the sections in any desired position of adjustment. By loosening the nut 13, the sections 5 and 6 may be adjusted, and, when adjusted, they are guided by the pins 10 and 12 and are held in proper lateral relationship by the head 11 and nut 13. The opposing faces of 80 the sections 5 and 6 are provided with co-acting teeth, as shown, to prevent relative longitudinal displacement thereof when the nut 13 is tightened.

The toe member 4 is adapted to extend 85 transversely beneath the forward portion of the horseshoe 2, and the sides thereof are provided with upwardly and inwardly extending projections 14 which are adapted to engage the outer face of the horseshoe 2 on 90 the respective forwardly converging sides thereof. The toe member 4 has formed thereon a rearwardly extending arm 15, the free end of which is screw-threaded and extends centrally through and beyond the slots 95 8 and 9 in the sections of the heel member 3. Screwed on to the arm 15 is a nut 16, which, when tightened, draws the heel and toe members 3 and 4 toward each other and clamps the attachment to the horseshoe by drawing 100 the projections 14 and 7 into close engagement with the forwardly and rearwardly converging portions, respectively, of the outer face of the horseshoe 2. By loosening the nut 16, the heel and toe members 3 and 105 4 may be separated and the attachment removed from the horseshoe.

The heel and toe members are provided with suitable downwardly-projecting, anti-slipping calks 17, as shown.

I claim:

1. In an attachment for horseshoes, a heel

member adapted to extend transversely beneath a horseshoe and comprising two sections, each section having an upwardly extending projection adapted to engage one side of a horseshoe, said sections having co-acting teeth preventing relative longitudinal displacement of the sections when clamped together, and said sections being adjustable relatively to each other to adjust said projections toward and from each other, means to clamp said sections in different positions of adjustment, a toe member having upwardly extending projections adapted to engage the forward portion of a horseshoe, and means to connect said members.

2. In an attachment for horseshoes, a heel member adapted to extend transversely beneath a horseshoe and comprising a first section and a second section, each section having a slot therein and an upwardly extending projection adapted to engage one side of a horseshoe, and said sections being adjustable relatively to each other to adjust said projections toward and from each other, a pin projecting fixedly from the second section and through the slot in the first section and having a fixed head thereon confining the first section between it and the second section, a screw-threaded pin projecting fixedly from the first section and through the slot in the second section, a nut screwed on to the last-named pin and adapted to secure said sections in different positions of adjustment, a toe member having upwardly extending projections adapted to engage the forward portion of a horseshoe, and means to connect said members.

3. In an attachment for horseshoes, a heel member adapted to extend transversely beneath a horseshoe and comprising a first section and a second section, each section having a slot therein and an upwardly extending projection adapted to engage one side of a horseshoe, and said sections being adjustable relatively to each other to ad-

just said projections toward and from each other, a pin projecting fixedly from the second section and having a bar head thereon confining the first section between it and the second section when said sections are in parallel relation to each other and permitting the separation of said sections when one is turned at an angle relatively to the other, a screw-threaded pin projecting fixedly from the second section and through the slot in the first section, a nut screwed on to the last-named pin and adapted to secure said sections in different positions of adjustment, a toe member having upwardly extending projections adapted to engage the forward portion of a horseshoe, and means to connect said members.

4. In an attachment for horseshoes, a heel member adapted to extend transversely beneath a horseshoe and comprising a first section and a second section, each section having a slot therein and an upwardly extending projection adapted to engage one side of a horseshoe, and said sections being adjustable relatively to each other to adjust said projections toward and from each other, a pin projecting fixedly from the second section and through the slot in the first section and having a fixed head thereon confining the first section between it and the second section, a screw-threaded pin projecting fixedly from the first section and through the slot in the second section, a nut screwed on to the last-named pin and adapted to secure said sections in different positions of adjustment, a toe member having upwardly extending projections adapted to engage the forward portion of a horseshoe and having a screw-threaded arm extending through and beyond the slots in the sections of the heel member, and a nut screwed on to said arm to hold said members together.

In testimony whereof I affix my signature hereto.

SEIKICHI NORO.
